FIRING AND SAFETY MECHANISM FOR
RECOILLESS FIREARMSWilliam J. Kroeger and Clarence Walton Musser,
Philadelphia, Pa.

Application February 2, 1949, Serial No. 74,163

5 Claims. (Cl. 89—1.7)

(Granted under the act of March 3, 1883, as
amended April 30, 1928; 370 O. G. 757)

1

The invention described herein may be manufactured and used by or for the Government for governmental purposes without the payment of any royalty thereon.

The present application is a continuation of Application Serial No. 577,830 filed on February 14, 1945, now Patent Number 2,472,111, in the names of William J. Kroeger and C. Walton Musser for "Recoilless Firearm and Ammunition Therefor."

Our invention relates to firearms of the recoilless type, and it has special reference to non-recoil guns wherein the forces of rearward reaction that result from projectile discharge are neutralized by forwardly acting counterforces simultaneously set up by the propellant charge's combustion.

Broadly stated, the object of our invention is to improve the design and extend the usefulness of recoilless guns wherein the named recoil neutralization is effected by a rearward escape of generated powder gas through openings or orifices in the gun's breech.

A more specific object is to provide improved firing and safety mechanisms for such recoilless guns.

Other objects and advantages will become apparent as the disclosure and description hereof proceed.

In the aforementioned parent application we disclosed a number of factors to be necessary to a satisfactory operation of our inventive recoilless firearm. In constructing one recoilless firearm pursuant to that disclosure we: (a) make the gun's chamber substantially larger in diameter than the ammunition cartridge case which fits therein; (b) support this cartridge case centrally in the enlarged chamber solely from the two ends of the case; (c) provide in the gun's breech a rearwardly opening orifice of unique annular nozzle design that is capable of ready adjustment for optimum area; (d) use a cartridge case having a metal wall which is perforated throughout the length and circumference of the case and which permits discharge of propellant combustion gases radially against the chamber's surrounding wall and then rearwardly from the gun out through the annular orifice of the gun's breech; (e) pre-engrave the projectile for ready passage through the rifled bore of the gun's barrel, and (f) so coordinate the breech and firing mechanisms as to permit quick and convenient loading and firing.

The invention to which the present specification is essentially restricted is concerned with the

2

specific firing and safety mechanisms used in the gun first disclosed by the aforementioned parent application. The present invention, together with illustrative embodiments thereof, will thus be understood from the following description taken in conjunction with the accompanying drawings wherein:

Fig. 1 is a perspective view of a recoilless gun of 75 mm. caliber which incorporates our inventive features;

Fig. 2 is a rear view of the Fig. 1 weapon with the breech bar thereof horizontal and the breech block secured within the chamber where it constitutes the inner wall of an annular orifice;

Fig. 3 shows our weapon in rear elevation with the breech bar and breech block thereof rotated to the unlatched position;

Fig. 4 is a section on line 4—4 of Fig. 2 through hinge and breech bar rollers by which the firing mechanism's hammer is cocked upon each unlatching of the breech;

Fig. 5 is a section on line 5—5 of Fig. 2 showing further details of the breech block, locking devices therefor, the firing mechanism, trigger linkage, and the unique perforated cartridge case which characterizes ammunition usable with our novel weapon;

Fig. 6 is a view taken from line 6—6 of Figs. 5 to show from another vantage point the relationships of the trigger, the trigger key and the safety button;

Fig. 6A shows the mechanism of Fig. 6 after the safety button has been rotated to release the safety preparatory to firing by depression of the trigger;

Fig. 7 is an enlarged section on line 7—7 of Fig. 5 through the gun's trigger handle with the trigger and associated safety mechanism in place;

Fig. 7A shows the mechanism of Fig. 7 after the safety button has been rotated to release the safety (as from the Fig. 6 to Fig. 6A position) preparatory to firing by depression of the trigger;

Fig. 8 is an enlarged section on line 8—8 of Fig. 5 similar to Fig. 7 but taken from a different level of the trigger handle;

Fig. 9 is an enlarged reproduction of the hammer and cocking roller mechanisms first illustrated by Fig. 4;

Figs. 10—11—12—13—14—15—16 are views illustrative of how cocking of the hammer is effected by each unlatching rotation of the breech bar;

Fig. 17 is a rear elevation view of the gun with its breech block withdrawn from the chamber and swung downwardly on a supporting hinge; and

Fig. 18 is a side view of the gun taken from line 18—18 of Fig. 17.

The complete recoilless gun

Our inventive improvements are here illustratively disclosed as being incorporated in a military weapon of 75 mm. caliber capable of a completely recoilless firing of projectiles. As the description proceeds, it will become apparent that our improvements may also be applied to firearms of characters, sizes and shapes other than the one here disclosed and that the represented 75 mm. open-breech weapon thus has been chosen only to illustrate and not to limit the apparently wide application and scope by which these improvements are characterized.

The illustrative recoilless firearm here shown consists of a barrel 30; an enlarged chamber 31 secured to the rear of this barrel and having the uniquely tapered shape represented; a breech block 33 partially closing the rear of the chamber; a breech bar 34 secured to the block and carrying trigger and breech handles 35—36; a pair of carrying handles (one of which is shown at 38 in Fig. 1); and a sight (not shown) for aiming the gun in conventional manner.

Carrying handles 38, in conjunction with the trigger and breech handles 35—36, enable two or four men readily to carry the weapon from one location to another. When the gun is set up on a tripod (not shown) or other suitable support, firing of the weapon is controlled by trigger handle 35 conveniently grasped by the right hand of the user who places himself on the left side of the weapon ahead of the weapon's breech and in position to look through the sight (not shown) in training the gun on its target.

Although the aforementioned parent application sets forth in complete detail a description of the various component parts of our novel weapon, and this application is intended to disclose primarily the firing and safety mechanisms thereof, it will be well for a fuller understanding of the latter novel mechanisms if some of the related parts are herein described. Accordingly, there follows a brief description of the gun's chamber and breech, together with an outline of the manner in which our novel recoilless type weapon functions.

The chamber and breech

As here shown, the gun's chamber 31 takes the form of an enlarged cylinder uniquely tapered at its forward end and there affixed to the rear of barrel 30 in any integrally secure manner as by the aid of screw threads (not shown). This attachment of chamber and barrel may be effected in any desired manner such as by brazing or by use of the flange 45 which Fig. 1 shows. This flange has internal threads (not shown) which mate with similar threads (not shown) on the external surface of the barrel.

As the drawings show, the breech block is a "spider-like" element removably secured within the rear of chamber 31, and constitutes only a partial closure therefor; (see Figs. 1 to 5 inclusive). It takes the form of a cylindrical block 33 which is radially spaced from the chamber wall in a manner to form a substantially annular orifice that leads from the chamber's interior to the rear exterior of the gun. A section of this annular orifice is shown at 48 in each of Figs. 1 to 4 inclusive and Fig. 17. From those figures it will be seen that the breech block tapers inwardly from the front to rear.

Four locking lugs shown at 49 extend radially from the central breech block 33 and interfit with mating protrusions 50 on the chamber wall interior. Each locking lug 49 carries threads 5 on the periphery thereof and each mating protrusion 50 is provided with similar threads indicated at 51. When these two sets of threads are engaged as shown in Fig. 5, they securely lock the breech block 33 in the rear of the chamber.

When inserted and locked within the chamber 31 this breech block 33 constitutes a firm support for the ammunition which it helps to position within the weapon. The steel of its central core structure is of sufficient thickness and strength to withstand, with a factor of safety of well over two, the maximum rearward thrust exerted thereon during firing.

Cooperating with the gun's barrel and the just described chamber and breech structure is ammunition having the unique perforated case shown in Fig. 5. As explained in greater detail in the aforementioned parent application, the purpose of the perforations 69 in the cartridge case 40 is to permit the powder gases to issue therefrom 25 in a radial manner, so as to expand within the enlarged chamber 31 and become exhausted through the annular orifice 48 to the rear exterior of the gun with a torque equal but opposite in direction to that caused by a projectile (not shown) upon being fired through the gun's barrel.

In the loaded position represented by Fig. 5, the cartridge case head 63 is accordingly engaged by a mating recess 130 in the front of the breech block. This recess 130 flares outwardly toward 35 the front so as more conveniently to receive the case head during loading. By its engagement with the head, the rear of cartridge case 40 is centrally positioned within chamber 31 and the entire case is restrained against backward movement. Thus positioned, the primer (not shown 40 but contained within member 56) carried by the cartridge case head 63 is engageable by a firing pin 66 protruding through the center of the breech block 33 and there actuated by firing mechanism later to be described.

The annular orifice and recoil neutralization

Recoilless firearms of the open-breech type here considered neutralize the forces of rearward reaction by forwardly acting counterforces. 50 In our improved weapon these counterforces are produced by acceleration of the rearwardly escaping generated powder gases with an accompanying pressure gradient within the chamber and venturi. Therefore, the pressure forces rearwardly acting against the obstructions presented by the breech can be counteracted by the forwardly acting pressure forces on the small annular forward portion of the chamber 31, forwardly acting drag forces of the projectile (not shown) in the rifled (not shown) barrel 30, and by the forwardly acting force component produced by the pressure of expanding gases in the conical and divergent portions of the earlier indicated annular orifice 48 between the gun's breech block 33 and the rear wall of chamber 31 wherein this block is secured.

This annular orifice extends all the way around that block's central core or hub and is obstructed 70 only by the four locking lugs 49 which commence centrally from the common hub portion and terminate at their outward extremities in the breech locking lugs 29 for engagement with threads 51 of the protrusions 50 that extend 75 radially inward from chamber 31. All circum-

ferential space separating lugs 49 thus constitutes the named annular orifice 48 which leads from the interior of chamber 31 rearwardly to the exterior of the gun.

Upon ignition of the propellant powder 55 and the resultant discharge of the projectile (not shown) forwardly out of barrel 30, there is expelled through the perforations 60 of cartridge case 40 combustion gases which are projected radially against the surrounding chamber wall and then rearwardly out of the chamber through the annular orifice now being described. By thus acquiring momentum opposite to that of the forward moving projectile (not shown) the explosive gas thus expelled sets up the aforesaid counterforces which tend to neutralize recoil. In the aforesaid parent application there is described in detail the manner in which we supplement this momentum effect by making the annular breech orifice of the represented "nozzle" of cone shape. Also there described is the construction and function of the breech orifice adjusting cone 54 which the drawings of the present application show (see Fig. 4) but which need not be described here in any further detail, other than to state that screws 71 (see Figs. 5 and 9) serve to hold cone 54 in the illustrated position within the chamber 31.

The breech block carrier and lock mechanism

Explanation has already been given of how the breech block 33 is secured in the rear of chamber 31 by the aid of that block's locking lugs 49 and the mating protrusions 50 on the chamber interior. In the closed and locked position represented by Figs. 1, 2 and 5, this support is all that is needed to hold the breech block in place, and it is fully adequate to restrain the maximum chamber pressures, which combustion of the propellant charge 55 sets up.

To facilitate loading and removal of the cartridge case 40 after firing, provision is made for unlocking this breech block 33 from its chamber attachment, rearwardly withdrawing it from the chamber 31 and swinging it out of alignment with the chamber interior to the downward position such as that represented in Figs. 17-18. Aiding these actions is an operating member which illustratively takes the form of a pair of handles 35-35 which protrude from the breech bar 34, that is in turn secured to the breech block by means of screws 71 (Figs. 2-3). Intermediate this bar 34 and the main body of the breech block is an offset ring-like extension 79 of the hinge fixture 75. Around this ring extension both the breech block 33 and the bar 34 may be turned between the "horizontal bar" position of Figs. 1-2 and the "inclined bar" position of Fig. 3.

Counterclockwise rotation of the weapon's breech bar 34 serves to engage the breech block locking lugs 49 with the mating threads of chamber protrusions 50 and thereby secures the breech block 33 within the chamber 31 as earlier explained; clockwise rotation moves the locking lugs out of engagement with the chamber protrusions and into the circumferential region between protrusions (Fig. 3). In the latter position, the breech block 33 is freed for rearward withdrawal from the chamber and downward swinging around hinge pin 80 to the position represented by Figs. 17-18. Hinge pin 80, it will be seen from Fig. 18, extends through a hinge block 76 that is attached by screws (not shown) to chamber 31.

As reference to Fig. 5 will show, there is provided means in the form of a locking bar 89 which can manually be moved by a pin 88, but which is spring 91-loaded so as automatically to act in locking the breech against rotative turning when the breech block is in the closed position represented by Figs. 1, 2 and 5. When bar 89 is automatically so actuated, a central stepped position portion of bar 89 engages a slot 98 in ring-like extension 79 of hinge fixture 75 so as to lock the breech block 33 (see Fig. 5). This lock serves to prevent turning or opening of the breech block until the gun is fired. When the gun is fired, the forwardly moving hammer 92, by reason of the tapered bottom of a groove 106 in the hammer sidewall (with which the free end of bar 89 is in engagement) moves that bar against spring 91 so that the bar's stepped portion is removed from locking engagement 20 with groove 98. This function will become more apparent when the description of the firing mechanism is set forth below.

The firing mechanism

25 The unique mechanical type of firing mechanism which we have employed in our novel weapon permits an operator to fire the weapon by a simple pressing of the trigger 94 carried by handle 35. In the disclosed arrangement there is provided a firing pin 66 which is threadedly attached to the forward end of the hammer 92 as shown in Figs. 4, 5 and 9. In the cocked position which Fig. 5 illustrates, the firing pin and hammer are withdrawn to their rearwardmost 30 position which they attain by compressing spring 97. The hammer and firing pin are locked in this cocked position by means of sear 98 protruding into a groove 140 in the side of the hammer. When, as will be explained below in 35 more detail, sear 98 is withdrawn from groove 140, spring 97 expands thereby driving the hammer and firing pin forward with sufficient force so that the firing pin causes the primer (not shown) contained in percussion element 56, to 40 be detonated. Fig. 9 shows the fully expanded spring 97 and the position of the firing pin and hammer after firing.

It should be understood that the firing pin at all times moves in unison with the hammer. The 50 hammer, which takes the form of a metal cylinder, is shown in Figs. 14-15-16 in its relationship with the cocking rollers 100-101 whose function also will be described below.

Cocking of the hammer

Cocking of the hammer from the forward position of Fig. 9 to the rearward position of Fig. 5 is effected by rotation of the breech block 33 and its breech bar 34 from the "horizontal bar" position of Figs. 1-2 to the "inclined bar" position of Fig. 3. Such rotation is translated into rearward movement of the hammer by means of two pairs of rollers 100-101.

Rollers 100 are carried by the hinge ring 79 65 (see Figs. 5 and 9), while rollers 101 are carried by the breech bar 34. Both sets of the named rollers engage with longitudinal slots 103 in the outer surface of hammer 92. The forward portion of each of these slots is tapered as shown at 70 104 in Figs. 14-15-16.

With the breech block 34 in the horizontal position of Figs. 1-2, both sets of these rollers 100-101 lie along line 4-4 of Fig. 2 and sections therethrough appear as shown in Figs. 4 and 9. The 75 hammer 92 is shown by Fig. 9 in its forward or

fired position wherein firing pin 66 has by the hammer in spring 97 been moved to its forward limit of travel.

Upon rotation of the breech bar 34 from the horizontal position of Figs. 1-2 to the inclined bar position of Fig. 3 the forward or hinge rollers remain stationary, while the rearward or bar rollers 101 rotate the hammer clockwise as viewed from the rear, from the position shown in Fig. 12 to that indicated by Fig. 13. Fig. 12 will be seen to correspond to Fig. 10 except that Fig. 10 shows the hammer and its rollers as viewed from the forward end of the firing mechanism shown in Fig. 9.

The named rotative movement brings the tapered portion 104 of the hammer slot 103 against stationary rollers 100 and by a camming action which becomes apparent on comparing Figs. 15-16, forces the hammer 92 backwards against spring 97 and into the cocked position shown by Figs. 5 and 11. When the cocked position has been reached the sear shown at 98 in Fig. 5 is by spring action later to be described forced inwardly ahead of the rear face of a restraining slot shown at 140.

Release of the hammer

In this position the sear 98 holds the hammer cocked until such time as trigger 94 may be depressed. Upon such depression of the trigger, the sear is withdrawn from its engagement with the restraining slot 140, and hammer 92 plus firing pin 66 are allowed to move forward due to the expansive force of spring 97. This forward movement brings firing pin 66 against the ammunition's primer (not shown) contained in element 56 and thereby fires the weapon.

The main forward movement can, of course, take place only after the breech bar 34 has been returned to the horizontal position of Figs. 1-2. In that horizontal position bar rollers 101 are again realigned with hinge rollers 100 as shown in Fig. 11. This realignment frees the hammer for unrestrained forward movement as soon as sear 98 is withdrawn from the front of the latching slot 140 therein.

In the illustrative construction shown hammer 92 is fitted relatively close to the inner walls of hammer housing 93. In order that "air pumping" action resulting from the closeness of this fit will not restrain longitudinal movement of the hammer with respect to the casing, there is provided in the hammer's sides a second pair of longitudinal slots indicated at 167 in Figs. 10 to 13 inclusive. These slots allow free passage of air into the space behind the hammer upon forward or firing movement thereof, and from that rearward space upon backward or cocking movement thereof.

Complete hammer operation

The just described hammer mechanism will thus be seen to operate as follows. Following each firing of the weapon, the firing pin 66 and hammer 92 occupy their forward positions as shown by Fig. 9 while the breech block 33 is still locked in chamber 31 with the bar 34 horizontal as shown in Figs. 1-2.

Rotation of the breech bar 34 to the inclined position shown in Fig. 3 causes the bar rollers 101 to rotate the hammer 92 clockwise as viewed from the rear, and this action in turn causes hinge rollers 100 to cam the hammer 92 backwardly against spring 97 as already explained. The so-cocked hammer now occupies the position shown

in Fig. 5. Retention in that position is effected by sear 98 blocking forward movement of the hammer as likewise shown in Fig. 5.

This blocking continues during subsequent withdrawal of the breech block 33 from the chamber to the position shown by Figs. 17-18. It also remains effective during reinsertion of the breech block into the chamber and engagement therewith by restoration of breech bar 34 to the horizontal position of Figs. 1-2. Such restoration realigns rollers 100-101 from the condition shown by Fig. 16 to that indicated by Fig. 14.

This re-alignment conditions the hammer for subsequent forward movement upon withdrawal 15 of the restraining sear 98. Upon such withdrawal 16 of the restraining sear 98, upon such withdrawal 17 of the restraining sear 98. Upon such withdrawal 18 of the restraining sear 98, upon such withdrawal 19 of the restraining sear 98, upon such withdrawal 20 of the restraining sear 98, forces the hammer and its firing pin 66 rapidly forward into contact with the cartridge case's primer (contained in element 56) and thereby detonates the primer and fires the round 21 contained within the weapon.

By this action the firing mechanism is returned to the original "after firing" condition with which this description started.

The trigger safety mechanism

Cooperating with the hammer 92 and its just described cocking mechanism are trigger and safety mechanisms which will not be explained. These mechanisms utilize the earlier mentioned sear shown at 98 in Fig. 5, the earlier mentioned trigger shown at 94 in the same figure as protruding from the forward end of trigger handle 35; and a rotatable safety button 109 carried in the hollow end of that handle as also shown by Fig. 5, as well as Figs. 7-7A.

The sear 98 takes the form of a round rod slidably housed in the left half of breech bar 34 between the rear wall of that bar and a front cover plate 108 and having an outer end which is 30 inclined as shown by Fig. 5 into a mating opening in the inner end of the plunger-like trigger 94. This trigger is axially movable within handle 35 and safety fixture 109, but is by a key 111 prevented from rotation with respect thereto. 40 By a "double action" of a trigger spring 110 this trigger 94, when not depressed into firing position, is urged toward its outward limit of travel. This travel limit normally would be the safety button 109's opposed lower or inner projections 114; however, the intervening agency of the spring 110, being connected to the safety button below projections 114 and also connected to the trigger 94, limits such travel to the distance over which spring 110 may be compressed against projections 114. Such urging holds sear 98 against hammer 92 as shown in Fig. 5.

As Fig. 5 shows, spring 110 not only exerts tension between parts 94 and 109 but it also is arranged to impart turning effort on safety button 109 with respect to trigger 94, as will be more fully explained below. Incident to this turning effort use is made of the key 111 which passes through an opening in the trigger 94 and by engagement with longitudinal slots 112 inside the trigger handle 35 prevents rotation of the trigger within that handle while at the same time permitting axial trigger movement with respect to the handle.

Safety button 109 is provided with step-like 70 slots 159 through which the ends of trigger key 111 protrude as shown by Figs. 5-6-6A-7-7A. The trigger spring 110 encircles the trigger rod 94 as shown in Fig. 5. The two ends of this spring respectively are attached: (a) to an enlarged portion 162 of that rod shown in Fig. 5

at the sear-engaging end thereof; and (b) to the inner end 141 of the safety fixture 109 (again see Fig. 5).

During assembly of the parts shown in Fig. 5 this spring is so wound onto its two end attachments that upon insertion of the trigger key 111 through the step-like slots 150 and the trigger, the safety button 103 has exerted thereon a torque tending to rotate clockwise with respect to the trigger. (In this and later references to rotative directions with respect to the trigger, the directions should be considered as they would appear when viewed from the trigger's outer end—i. e., where it protrudes from handle 35—towards the trigger's opposite or inner end.) This rotative urge positions the step-like safety slots 150 as shown in Figs. 56 and thereby safeguards the trigger 94 against accidental depression into the gun's handle 35.

To insert the safety mechanism of Fig. 5 into the trigger handle 35, the trigger 94 in relation to the safety 109 is depressed and rotated to its fullest extent so as to align key 111 with the projections 114. Following insertion of the parts into the trigger handle 35 the trigger safety button's opposed lower projections 114 fit into an annular groove 115 that extends completely around the trigger handle's interior as shown in Figs. 5 and 8. Such fitting holds the assembly of Fig. 5 in place within the trigger handle. Under this condition the safety fixture 109 is free only for rotation with respect to that handle 35 while the trigger rod 94 is free only for axial movement through the handle and fixture.

Conditioning the safety for firing

It has now been seen that trigger spring 110 urges the sear-end of trigger 94 outwardly toward the safety 109 and at the same time urges button 109 clockwise with respect to the trigger and pin 111 extending therethrough. These two actions respectively hold the sear 98 against the gun's hammer 92 and maintain the side or step-like slots 150 of safety 109 in the position of Figs. 5-6 to restrain inward movement of the trigger.

The rotational force on the safety button 109 at all times assists the tension force of the trigger spring 110 in forcing the sear 98 inwardly toward the hammer 92. This is accomplished by the cam surfaces of the step-like slots 150 in the safety button 109 engaging with the trigger key 111. This essentially has the effect of retaining the sear in position by a wedge-like action to make its operation more positive.

In order to condition the weapon for firing it is only necessary to turn the safety button 109 counterclockwise as viewed in Fig. 5 through an angle of approximately 45 degrees. The relative position of the parts is shown in the drawings, Figs. 6-7, showing their position before turning, whereas Figs. 6A-7A show the parts after turning. Such turning removes the slot sidewalls of fixture 109 from the path of inward travel taken by trigger key 111. Depressing force now applied to trigger 94 results in inward movement thereof which pulls the sear 98 outwardly away from hammer 92 and thereby releases same for forward firing movement under the expanding action of spring 97.

Such firing of the weapon, moreover, is possible only when safety 109 is held in the counterclockwise-turned position against the clockwise restoring torque of spring 110. Under this condition the trigger 94 may be depressed as just

described. Under all other conditions spring 110 holds safety 109 in the position of Fig. 5 wherein depression of the trigger and firing of the weapon are effectively prevented.

Summary

From the foregoing it will thus be seen that we have improved the design and extended the usefulness of recoilless guns wherein recoil neutralization is effected by a rearward escape of generated powder gas through openings or orifices in the gun's breech, and that we have provided improved firing and safety mechanisms for such recoilless guns.

15 Our inventive improvements thus are capable of wide application and hence are not to be restricted to the specific form here shown and described by way of illustration.

We claim:

20 1. In a firearm, the combination of a barrel, a chamber extending rearwardly therefrom, a breech block in the rear of said chamber, a bar extending across and secured to the rear of said breech block, a firing pin carried by said breech block, a hammer secured to and extending rearwardly from said firing pin, a compression spring behind said hammer, a hammer housing protruding rearwardly from said bar and surrounding said spring and said hammer whereby to support the former and guide movement of the latter, cocking means for moving said hammer and firing pin backwardly against the compression of said spring, sear means for restraining same in said cocked position, and trigger means for causing said sear means to release said hammer and firing pin for forward movement.

2. In a firearm, the combination of a chamber, a breech block movable into and out of the rearward portion of said chamber, a bar extending 40 across and secured to the rear of said breech block, a handle affixed to said bar for transmitting operating movements to the breech block, firing pin and hammer members disposed within said breech block at a point traversed by said bar and movable with respect to the block and bar between a forward released position and a rear cocked position, a spring urging said hammer and firing pin towards said forward released position, cocking means for moving said hammer and firing pin backwardly against said spring and into said cocked position, a sear carried by and axially movable with respect to said breech block bar and normally effective to engage said hammer and latch same in said cocked position, 50 a trigger carried by said bar handle and resiliently protruding therefrom, and means interconnecting said trigger with said sear in a way which causes depression of the trigger into said handle to withdraw said sear from said latching engagement with said hammer.

3. In a firearm, the combination of a chamber, a breech block therein, a bar extending across and secured to the rear of said breech block, a handle affixed to said bar, a hammer disposed within said breech block at a point traversed by said bar and movable with respect to the block and bar between a rear cocked position and a forward released position, a sear carried by and axially movable with respect to 65 said bar and effective to engage said hammer and lock same in said cocked position, a trigger carried by said bar handle and interconnected with said sear in a way which causes depression of the trigger into the handle to withdraw said sear from said latching engagement with said ham-

mer, and resilient means urging said sear into said latching engagement and holding said trigger protruded from said handle.

4. In a firearm, the combination of a breech block, a bar extending thereacross, a handle affixed to said bar, a hammer disposed within said breech block and movable with respect to the block and said bar between a rear cocked position and a forward released position, a sear carried by said bar and effective to engage said hammer and lock same in said cocked position, a trigger protruding from said handle and interconnected with said sear in a way which causes depression of the trigger to withdraw the sear from said latching engagement with said hammer, means resiliently urging said sear into said latching engagement and resiliently holding said trigger protruded from said handle, and a safety button portion of said handle encircling said trigger and resiliently held in a first rotative position where depression of the trigger is mechanically prevented but turnable into a second rotative position where said trigger is freed for depression.

5. In a firearm, the combination of a breech block, a handle supported therefrom, a hammer movable with respect to said block between a rear

cocked position and a forward released position, a sear engaging said hammer and latching same in said cocked position, a trigger protruding from said handle and interconnected with said sear in a way which causes depression of the trigger to withdraw the sear from said latching engagement, a safety button portion of said handle effective in a first rotative position to make depression of said trigger impossible and effective in a second rotative position to free the trigger for such depression, and resilient means operative to urge said sear into engagement with said hammer and also to hold said trigger protruded from said handle and said safety button in its 15 said first rotative position.
